GAME BOARD

Filed Dec. 22, 1922

FIG. 2

FIG. 1

A. L. Roberts
Inventor

234

John Harpman

Attorney

UNITED STATES PATENT OFFICE.

ALVA L. ROBERTS, OF HUBBARD, OHIO.

GAME BOARD.

Application filed December 22, 1922. Serial No. 608,564.

To all whom it may concern:

Be it known that ALVA L. ROBERTS, a citizen of the United States of America, residing at Hubbard, in the county of Trumbull and State of Ohio, has invented certain new and useful Improvements in Game Boards, of which the following is a specification.

This invention relates to game board or apparatus, and the object thereof, is to provide an improved device of this class which is designed to amuse and entertain both old and young.

In this device the game is played with three marbles, first being red, another white, and another blue. The marbles are released at one end of a game board, where the marbles pass between a plurality of pins, and then travel down an incline, being deflected by means of a number of guides placed on the incline board. As the marbles roll over the guides they finally reach a plurality of pockets, that are colored, red, white and blue. The game may be played giving a certain number as a winning point for each pocket.

The drawing illustrates the preferred embodiment of the invention. However, it is to be understood that in adapting the same to meeting different conditions, various changes in the form, and minor details of construction may be resorted to without departing from the nature of the invention as claimed and set forth in the drawing:

Figure 1 is a perspective view of the game device.

Figure 2 is a detailed sectional view taken on lines 2-2 of Figure 1.

In the construction of my invention, I have provided an inclined board 1 which has sides 2 and a lower end 3. The board 1 is placed on an incline by means of support 4 which may be secured so that the same may be folded against the under side of the board 1 when not in use. This may be done by releasing a brace rod 5 (see Figure 2), when folding the same.

The device consists of a plurality of pins 6 spaced equally apart and located at the upper end 7 of the board 1. The sides 2 are provided with inturned guides 8, 9, and 10. Between the guides 8 are positioned guides 11 and 12 which are similar in construction, but located on opposite sides of the central

55 inturned guides 13 and 14 which are irregular as to their position. Directly below the guides above mentioned, between the guides 8 are located 3 arch-shaped guides 15, 16, and 17. These guides are positioned in a line parallel to the row of pins 6. Directly below the guides 15, 16, and 17 are placed 2 arch-shaped guides 18 and 19 which are positioned in staggered arrangement, in reference to the arch-shaped guides 15, 16, and 17. The outwardly turned 60 guides 20 and 21 are located below the side of the inturned guides 9 centrally located and below the out turned guides 20 and 21 there is positioned a single arch-shaped 65 guide 22. On each side of this arch-shaped 70 guide 22 there is located straight guide members 23 and 24. These guide members are located so that the lower ends 25 of the same point inwardly, at any desired degree.

In playing this game, the marbles are 75 taken from a receptacle 26, positioned underneath the end 7 and held in position by means of a bracket 27. These marbles are released at any position about the pins 6 and are allowed to travel by means of gravity 80 down the inclined board 1, pass through the guides above described until the marbles finally reach a series of pockets 31, 32, and 33. These pocket bottoms may be colored, if desired, to correspond with the colors of the marbles used, such as red, white, 85 and blue. There is a central pocket 34 located at the bottom of board 1, which is divided by means of a painted boundary line in place of partition walls 35 as are used to 90 separate the series of pockets above referred to. This central pocket 35, having the bottom painted into divisions corresponding with the colors of the marbles used.

What I claim is:

95 In a device of the class described, an inclined board, side walls attached to said board, a lower end secured to said side walls, a plurality of pins equally spaced apart positioned parallel and located near the upper end of said inclined board, a series of inturned guides turning inwardly from the side walls, a plurality of inturned and out turned guides, positioned in a line between the upper side wall guides, a plurality of arch-shaped guides positioned in staggered arrangement, a pair of outturned guides positioned below the above men-

tioned arch-shaped guides, a centrally located arch-shaped guide positioned below the pair of out turned guides, a pair of straight guides positioned on each side of the single arch-shaped guide, a series of three pockets formed at the lower end of the inclined board, a pocket positioned between

said series of pockets, substantially as described for the purpose set forth.

In testimony whereof I affix my signature.

ALVA L. ROBERTS.
